UNITED STATES PATENT OFFICE.

CHARLES OSCAR ULLIN, OF KENDALLVILLE, INDIANA, ASSIGNOR TO McCRAY REFRIGERATOR COMPANY, OF KENDALLVILLE, INDIANA, A CORPORATION OF INDIANA.

DESIGN FOR A REFRIGERATOR.

46,707.

Specification for Design.

Patented Nov. 24, 1914.

Application filed June 22, 1914. Serial No. 846,694. Term of patent 7 years.

To all whom it may concern:

Be it known that I, CHARLES OSCAR ULLIN, a citizen of the United States, residing in Kendallville, in the county of Noble, State of Indiana, have invented a new, original, and ornamental Design for Refrigerators, of which the following is a specification, reference being had to the accompanying drawing, forming a part thereof.

The figure is a perspective view of a refrigerator.

I claim:

The ornamental design for a refrigerator, as shown.

CHARLES OSCAR ULLIN.

Witnesses:

R. V. STILES,
H. B. DUGAN.
